United States Patent Office

Des. 182,180
Patented Feb. 25, 1958

182,180

SHOPPING CART

Wolfe Grebow, Baltimore, Md.

Application February 13, 1957, Serial No. 44,858

Term of patent 14 years

(Cl. D14—3)

Fig. 1 is a perspective view of the shopping cart embodying my new design;

Fig. 2 is a side view thereof;

Fig. 3 is a top view thereof; and

Fig. 4 is a bottom view thereof, with the shopping cart being in a collapsed condition.

What is claimed is:

The ornamental design for a shopping cart, as shown.

References Cited in the file of this patent

UNITED STATES PATENTS

D. 155,640	Stoll	Oct. 18, 1949
2,468,604	Salat	Apr. 26, 1949
2,589,044	Brodeck	Mar. 11, 1952
2,738,984	Korchan	Mar. 20, 1956